W. H. EDWARDS.
COVERING FOR BOOKS.
APPLICATION FILED JAN. 21, 1921.

1,375,040.

Patented Apr. 19, 1921.

WITNESS:

Geo. L. Chapel

Inventor:

William H. Edwards
By Cyrus W. Rice
His Attorney.

UNITED STATES PATENT OFFICE.

WILLIAM H. EDWARDS, OF GRAND RAPIDS, MICHIGAN.

COVERING FOR BOOKS.

1,375,040.

Specification of Letters Patent. Patented Apr. 19, 1921.

Application filed January 21, 1921. Serial No. 438,838.

To all whom it may concern:

Be it known that I, WILLIAM H. EDWARDS, a citizen of the United States, residing at Grand Rapids, in the county of Kent and State of Michigan, have invented new and useful Improvements in Coverings for Books, of which the following is a specification.

The present invention relates to coverings for books, particularly for loose-leaf binders, and its object is to provide such a covering which may be readily adjusted to such books or binders of different thicknesses.

This and any other objects appearing hereinafter are attained by, and the invention finds preferable embodiment in, the structure hereinafter particularly described and illustrated by the accompanying drawings, in which:

Figure 1 is a front or plan view of a loose-leaf binder of the type known as a "post binder," certain parts being broken away;

Fig. 2 is a sectional view of said loose-leaf binder taken on planes corresponding to line 2—2 of Fig. 1, the parts broken away in Fig. 1 however being shown in Fig. 2;

Fig. 3 is a sectional view of the same taken on a plane corresponding to line 3—3 of Fig. 1; and

Fig. 4 is a sectional view of said loose-leaf binder taken on a plane corresponding to line 4—4 of Fig. 1.

In the embodiment of the invention chosen for illustration by the drawings and for detailed description in the body of this specification, my covering is shown applied to a book known as a loose-leaf post binder, in which the loose leaves 1 are held in place by posts 2 extending through orifices 3 in the leaves' binding portions, such posts being carried by the binding portion 4 of one cover—the back cover 5—and extending through the binding portion 6 of the other cover—the front cover 7. The body portions 8 of these covers 5 and 7 are joined to their said binding portions 4 and 6 by their flexible intermediate portions 9 respectively.

My covering comprises a pair of sheaths, for the covers 5, 7 respectively, into one of which sheaths 10 the outer edge 11 of the front cover 7 is thrust, and into the other sheath 12 the outer edge 13 of the back cover 5 is thrust in like manner. One sheath, as 10, has a flexible sheet 14, forming a back for the book or binder, and extending

from said sheath's outer wall 15 around the binding edge of the leaves 1 and into the sheath 12, passing between its outer wall 16 and the cover 5 of the binder or book therein. The free end of this sheet has a strap portion 17 which extends around the outer edge 13 of said cover 5 and thence through an opening 18 in the inner wall 19 of said sheath 12.

It will be seen that the free end of this strap 17 may be drawn by hand to cause both covers 5, 7 to be seated in the bottoms of their respective sheaths 10, 12 and to tighten the sheet 14 on the edges 20 of the binding portions 4, 6 of the book's covers.

The sheet 14 may have openings 21 therethrough, between the sheaths, and adapted to receive, or permit access to, the posts 2 of the binder and the means for adjusting the binder to leaf bodies of different thickness. Other means for adjusting the sheet 14 in desired position relatively to the sheath 12 may be adopted as desired.

The invention being intended to be pointed out in the claims, is not to be limited to or by details of construction of the particular embodiment thereof illustrated by the drawings or hereinbefore described.

I claim:

1. In a device of the character described; a pair of sheaths for the covers respectively of a book into which sheaths the outer edges of said covers respectively are thrustable, one of the sheaths having an opening 90 through its inner wall and the other sheath having a flexible sheet extending from its outer wall and into the first mentioned sheath between its outer wall and the book's cover therein and having a strap portion extending around the outer edge of said cover and through said opening.

2. In a device of the character described; a pair of sheaths for the covers respectively of a post binder into which sheaths the outer edges of said covers respectively are thrustable, one of the sheaths having an opening through its inner wall and the other sheath having a flexible sheet extending from its outer wall and into the first mentioned sheath between its outer wall and the binder's cover therein and having a strap portion extending around the outer edge of said cover and through said opening, the flexible sheet having an opening 110 therethrough between the sheaths and adapted to receive the post of said binder.

3. In a device of the character described; a pair of sheaths for the covers respectively of a book into which sheathes the outer edges of said covers respectively are thrustable, 5 one of the sheaths having a flexible sheet extending from its outer wall and around the binding edge of the book and into the

other sheath between its outer wall and the book's cover therein; means for adjusting said sheet relatively to said second sheath. 10

In testimony whereof I have hereunto set my hand at Grand Rapids, Michigan, this 18th day of January, 1921.

WILLIAM H. EDWARDS.
